UNITED STATES PATENT OFFICE.

ORTON A. PECK, OF KEENE, NEW HAMPSHIRE.

MILK COOLER.

Application filed September 7, 1928. Serial No. 304,604.

This invention relates to a device for cooling bottles of milk by the evaporation process. The principal objects of the invention are to provide a cooling device which will 5 be simple and convenient to operate and can be used over and over again and which can be put out-doors at night, located one side up, so that the liquid will not leak out, and can be turned over a milk bottle in the morning without the manipulation of any valves or other devices and will apply to the outside of the bottle a cooling medium in such form that it will evaporate and keep the bottle cool for several hours. Also to provide 10 a container for the water in co-operation with a distributor cup which, when inverted, will supply an absorbent medium with the necessary liquid.

Other objects and advantages of the invention will appear hereinafter.

Reference is to be had to the accompanying drawings in which—

Fig. 1 is a side view of a preferred form of the device shown in position over a milk 25 bottle;

Fig. 2 is a diametrical sectional view thereof;

Fig. 3 is a similar sectional view of the device shown in its position when not in 30 use; and

Fig. 4 is an elevation showing another way in which the device can be applied to an empty bottle ready to be inverted over a new bottle when it is delivered.

It is customary to deliver milk bottles in exposed places where they are likely to receive the rays of the sun for several hours before they are taken in. This invention is designed for the purpose of cooling the 35 same for several hours until such time as the bottles may be taken in, but the invention is capable of use for cooling purposes under other conditions and under other circumstances.

The cooler consists of a cylinder 10 of 45 textile material such as canvas, felt or the like which, for the purpose of stiffening it, is provided with a casing 11, preferably of skeleton form, to which the cylinder 10 is 50 secured at the top and bottom if desired. At any rate, the skeleton frame 11, which can be formed of sheet metal, for example sheet aluminum, can be provided with wide openings therethrough which will furnish a stiffener for the fabric and hold it in place as 55 shown in Fig. 1. This cylinder 10 is formed

of absorbent material for the purpose of receiving water or other liquid and readily evaporating it to keep down the temperature of a milk bottle to which it is applied. 60

In the position shown in Fig. 1, it has at the top a distributor 12, which consists of a cup-shaped piece of metal having fine perforations around it near the top and other perforations lower down but spaced farther apart so as to reduce the amount of liquid flowing out of it after the absorbent material is first soaked. It also has a neck 13 which is cylindrical outside and registering with the skeleton casing 11, that is, nearly 65 the same diameter, and provided with an internal screw thread. Into this screw thread fits the end of a cup 14 which is the same external diameter just mentioned. These parts can be formed of aluminum or other 70 metal, as may be convenient and inexpensive. The fabric shown at 10 extends to the end of the skeleton casing 11.

In the use of the device, it is turned up in the position shown in Fig. 3, liquid is placed 75 in the cup 14, which preferably is filled to its top level, then the distributor cap 12 is screwed down on it, and the textile cylinder 10 is put down over that with the casing 11 outside it. These parts fit well 80 enough so that they will stand in that position, as shown in Fig. 3. If desired, the metallic casing 11 can be provided with a hook 85 16 and the device can be supported on an empty milk bottle, as indicated in Fig. 4, 90 depending from the hook. In this case, the parts 10, 11 and 12 have to fit each other with enough friction to prevent the cup, when filled with liquid, from dropping off.

In either this form or in the form shown 95 in Fig. 3, the cup is filled and put out with the empty milk bottles at night. In the morning the new milk is delivered and the milkman turns this device bottom side up and puts it over the fresh bottle of milk. 100 The result of this is that the liquid oozes out the perforations in the distributor 12 and at first a large amount of liquid comes out at the top and soaks the textile cylinder 10 so that it will be thoroughly wet. 105 After the level of liquid gets down below the upper level of holes 12, the rest of the liquid will drain out more slowly. Immediately after this cylinder is wet in this way the liquid will commence to evaporate and the 110 bottle of milk, which is already cooled, will thus be kept cool as long as this evaporation.

takes place. The parts are designed in such proportions that this period of evaporation will last for several hours, owing to the fact that as the liquid evaporates, more will take its place coming through the lower rows of perforations. There will be no danger of the milk having soured before it is brought into the house under ordinary circumstances.

The device is of durable materials and the textile material preferably is heavy enough so that it will stand any strain to which it is likely to be put and will last for a long time if used over and over. The parts are easily separated for cleaning and for refilling, but it has to be filled every day when it is in use. It constitutes an effective device which is convenient to handle and manipulate for keeping milk bottles cool.

Although I have illustrated and described only two forms of the invention, I am aware of the fact that other modifications can be made therein by any person skilled in the art without departing from the scope of the invention as expressed in the claims. Therefore, I do not wish to be limited to all the details of construction herein shown and described, but what I do claim is:—

1. In a device for cooling articles by evaporation, the combination of a cup for receiving liquid with a distributor adapted to be secured to the top of the cup when the liquid is poured in, and a piece of absorbent material depending from the distributor and in position to receive the liquid through the distributor on its surface, said distributor being provided with perforations through its side walls for supplying the textile material with liquid from the cup when inverted over the article to be cooled.

2. In a device for cooling milk bottles by evaporation, the combination of a cup for receiving liquid with a distributor adapted to be secured to the top of the cup when the liquid is poured in, and a piece of absorbent material depending from the distributor when inverted, said distributor having per-

forations through its side walls arranged nearer together at the top of the distributor when inverted over a milk bottle than at the bottom, whereby when first inverted, a considerable body of liquid will be supplied to the fabric and it will continue to give off smaller quantities for some period of time afterwards to compensate for evaporation.

3. In a device for keeping an article cool, the combination of a cup at the end adapted to remain full of liquid until inverted, with a distributor secured to the cup over its open end and having perforations through its side walls through which the liquid will be discharged slowly and a cylinder of absorbent material covering the side wall of the distributor and secured thereto and depending therefrom around the article to be cooled.

4. In a device for keeping an article cool, the combination of a cup at the top adapted to remain full of liquid until inverted, with a distributor secured to the cup over its open end and having perforations through its side walls through which the liquid will be discharged slowly, a cylinder of absorbent material covering the side wall of the distributor and secured thereto and depending therefrom around the article to be cooled, and a skeleton frame around the outside of said cylinder of textile material to hold it in position.

5. In a device for cooling articles by evaporation, the combination of a reservoir to contain the liquid to be evaporated and a distributor for distributing the liquid to the evaporating medium, and an evaporation medium, the combination being so constructed and arranged that the device acts as a reservoir until evaporation and cooling are desired when inverting the device starts distribution and evaporation of the liquid.

In testimony whereof I have hereunto affixed my signature.

ORTON A. PECK.
